UNITED STATES PATENT OFFICE.

WILLIAM J. BRENNAN, OF SWAMPSMOTT, MASSACHUSETTS, ASSIGNOR TO UNITED SHOE MACHINERY CORPORATION, OF PATERSON, NEW JERSEY, A CORPORATION OF NEW JERSEY.

MACHINE FOR BEVELING EDGES OF BUTTONHOLES.

Application filed March 21, 1919. Serial No. 284,148.

To all whom it may concern:

Be it known that I, WILLIAM J. BRENNAN, a citizen of the United States, residing at Swampscott, in the county of Essex and State of Massachusetts, have invented certain Improvements in Machines for Beveling Edges of Buttonholes, of which the following description, in connection with the accompanying drawings, is a specification, 5 like reference characters on the drawings indicating like parts in the several figures.

This invention relates to cutting machines and is herein illustrated as embodied in a machine for beveling the edge of a button- 10 hole.

A pistol holster is commonly made of heavy leather and is provided with a closure in the form of a flap which is integral with one wall of the holster and may be bent over 15 the butt of the pistol and fastened to the outside of the opposite wall. The fastening mechanism commonly comprises a headed stud riveted or otherwise fastened to one wall of the holster and a buttonhole formed 20 in the free end of the flap. Owing to the heavy leather of the flap, it is difficult to push the buttonhole over the stud and to 25 pull it therefrom; and to overcome this difficulty it has been customary to relieve the 30 buttonhole by beveling the eye and slit there- 35 of by means of a hand knife. This operation is slow and inaccurate; and the general object of this invention is to provide a machine for accomplishing this and similar

According to one feature of the invention, two cutters are provided, one shaped to bevel the eye and the other shaped to bevel the slit of the buttonhole; and located 40 beneath the cutters is a support for a piece of work having a buttonhole therein, provision being made for causing relative movement of approach between the cutters and the support. In the illustrative machine an 45 end milling cutter having a face shaped to bevel the eye of the buttonhole and a second milling cutter having a face shaped to bevel the slit of the buttonhole are mounted adjacent each other above a common work 50 support which is normally spaced from the cutters but may be raised by depressing a treadle. The cutters are rotated continuously, and the work is presented first to one and then to the other cutter. With such a

machine the edge of the buttonhole may be 55 beveled with extreme accuracy and much more rapidly than has hitherto been possible.

This and other features of the invention, including certain details of construction 60 and combinations of parts, will be described as embodied in an illustrative machine and pointed out in the appended claims.

Referring now to the accompanying drawings, 65

Fig. 1 is a perspective of a machine in which the present invention is embodied;

Fig. 2 is a detail principally in section showing the means for raising the table or work support; 70

Fig. 3 is a detail in section showing the manner in which the slit is beveled;

Fig. 4 is a similar detail showing the beveling of the eye, and

Fig. 5 is a perspective of a portion of a 75 piece of work which has been operated upon by the machine;

The work support or table comprises a main portion 7 and an auxiliary portion 9 which is adjustably mounted on the main 80 portion by means of a screw 11 which is threaded into a socket formed in a boss on the underside of the main portion 7. The upper end of this screw engages the lower end of a pin 13 the upper end of which carries the adjustable portion 9. By referring to Fig. 1 it will be seen that the upper surfaces of the portions 7 and 9 are horizontal and that the relative positions of the two 85 surfaces may be varied by manipulating the screw 11. Rotatable in vertical bearings in a bracket 15 is an upright shaft 17 having at its upper end a pulley 19 and at its lower end an end milling cutter 21. This cutter has a conical cutting face shaped to bevel 90 the edge of the eye 100 of the buttonhole; and, in order to center the cutter with respect to the eye, a guide is provided, herein shown as a pilot 23, located at the center of the cutting face of the cutter. 95

Rotatable in horizontal bearings formed in a bracket 25 is a shaft having fast thereon a pulley 27 and a flat milling cutter 29. The cutter is located above the main portion 7 of the work support and its cutting 105 face is shaped to bevel the edges of the slit 200 of the buttonhole to produce the effect illustrated in Fig. 5. In order to position

and hold the flap of the holster properly beneath this cutter with the slit in the plane of rotation of the cutter, there are provided a back gage 31, side gages 33, and a pair 5 of spring fingers 35 which are fastened by screws 37 to the back gage. The back gage 31 has a slotted extension located beneath the table, as shown in Fig. 3. Extending through this slot is a guide pin 39 and a cap 10 screw 41. Together these members serve to guide the gage while it is being adjusted; and the cap screw serves also to hold the gage in adjusted position. The side gages 33 are held in position by screws 43.

15 The work support 7 is carried at the upper end of a headed rod 45 which is slidably keyed in a bore in an upright boss 47. A coiled spring 49, which rests upon a collar 51 fast to the rod and bears at its upper 20 end against a shoulder, serves to maintain the table normally in the lowered position shown. One end of a lever 53 pivoted at 55 to a lug on the frame of the machine, extends beneath the rod 45, the other end of 25 the lever having pivoted to it a treadle-rod 57. Depression of a treadle (not shown), which is attached to the lower end of the rod, thus serves to raise the work support to an extent determined by an adjustable 30 stop screw 59.

In the operation of the machine, power is applied to the shafts of the cutters in any suitable manner, as for example by the belts 61 and 63, to rotate them continuously. 35 The flap of the holster having the button-hole cut in it is placed upon the portion 9 of the work table and the treadle manipulated to raise the table. At the same time the operator manipulates the work so as 40 to cause the pilot 23 to enter the eye of the buttonhole. The effect of this is to center the cutter 21 with respect to the eye and to bevel the edge of the eye as shown in Fig. 4. The treadle is then released and the flap 45 of the holster placed upon the portion 7, being properly positioned by contact of its edge with the back gage 31 and the side gages 33. The table is then raised to bevel the edges of the slot after which the table 50 is lowered. In Fig. 3 the work is shown in place after the lowering of the table, the outline of the cutter 29 being indicated in dot and dash. The vertical adjustment of the portion 9 of the work support with 55 respect to the portion 7 permits the relative heights of the two portions to be varied so as to provide for unequal wear of the cutters due to grinding as well as to ensure that the work may be properly presented to 60 them. The set screw 59 limits the height to which the whole work support may be raised, one function being to take care of work of different thicknesses, and another to control the extent of the bevel.

65 Having thus described my invention, what

I claim as new and desire to secure by Letters Patent of the United States is:

1. A machine of the class described, having in combination, a support for a piece of work having a buttonhole therein, a cutter located above one portion of the support and shaped to bevel the edge of the eye of the buttonhole, a second cutter located above an adjacent portion of the support and shaped to bevel the edges of the slit of the buttonhole, and means for causing relative movement of approach between the work support and the cutters. 70 75

2. A machine of the class described, having in combination, a support for a piece of work having a buttonhole therein, a conical end milling cutter, a pilot adapted to enter the eye of the buttonhole to guide the cutter, a second milling cutter rotatable about an axis at an angle to that of the end cutter, 80 guides for locating the slit of the buttonhole beneath the second cutter, and means for raising the support toward the cutters.

3. A machine of the class described, having in combination, a support for a piece of work having a buttonhole therein, said support comprising a main portion and a portion adjustable with respect to the main portion, a conical end milling cutter located above one portion, a pilot adapted to center 90 the cutter with respect to the eye of the buttonhole, a second cutter located above the other portion and shaped to bevel the edges of the slit of the buttonhole, and treadle-controlled means for raising the support. 100

4. A machine of the class described, having in combination, a frame, a spindle slideable in the frame and carrying a support for a piece of work having a buttonhole therein, a rotary cutter for beveling the 105 edge of the eye of the buttonhole, a guide for centering the cutter with respect to the eye, a lever directly engaging the end of the spindle for moving the support toward the cutter and means engaging the lever for 110 variably limiting the extent of the movement to provide for pieces of work of different thicknesses.

5. A machine of the class described, having in combination, a support for a piece of 115 work having a buttonhole therein, a rotary end milling cutter having a conical cutting face, a guide for centering the cutter in the eye of the buttonhole, a spring for normally retaining the support in a work receiving position, and means for causing movement of the support toward the cutter against the tension of the spring. 120

6. A machine of the class described, having in combination, a support for a pistol 125 holster flap having a buttonhole therein, an end milling cutter, for beveling the edge of the buttonhole, and means for moving the support toward the cutter variable distances to vary the width of the bevel. 130

7. A machine of the class described, having in combination, a support for a pistol holster flap having a buttonhole therein, an end milling cutter, a guide for centering the cutter with respect to the eye of the button-hole, means for raising the support to cause the cutter to bevel the edge of the eye, and adjustable means independent of the centering guide for predetermining the height to 10 which the support is raised so as to vary the width of the bevel.

8. A machine of the class described, having, in combination, a support for a pistol holster flap having a buttonhole therein, a flap milling cutter shaped to bevel the slit of the buttonhole and mounted to rotate in the plane of the slit, an end gage for positioning the flap beneath the cutter, and a spring finger for holding the work in position against the gage. 15

9. A machine of the class described, hav-

ing in combination, a support for a pistol holster flap having a buttonhole therein, a milling cutter shaped to bevel the slit of the buttonhole, an end gage and side gages 25 for positioning the flap beneath the cutter, and means for causing relative movement of approach between the cutter and the support.

10. A machine of the class described, having in combination, a support for a piece of work, said support comprising a main portion and an auxiliary portion, a rotary cutter located above the main portion, a second cutter located above the auxiliary portion, and means for varying the position of the auxiliary portion with reference to the main portion to provide for unequal 30 35 wear of the cutters due to grinding.

In testimony whereof I have signed my name to this specification.

WILLIAM J. BRENNAN.
